US00D495049S1

(12) **United States Design Patent** (10) Patent No.: **US D495,049 S**
Austin (45) Date of Patent: **** Aug. 24, 2004**

(54) **OXYGEN CONSERVING REGULATOR**

(75) Inventor: **Gary Austin**, Euclid, OH (US)

(73) Assignee: **Taga Medical Technologies, Inc.**,
Eastlake, OH (US)

(**) Term: **14 Years**

(21) Appl. No.: **29/185,301**

(22) Filed: **Jun. 24, 2003**

(51) LOC (7) Cl. **29-02**

(52) U.S. Cl. **D24/110.6**

(58) Field of Search D24/110.6, 129;
128/204.26, 205.24, 202.27, 205.11, 205.14,

(57) **CLAIM**

The ornamental design for a oxygen conserving regulator, as shown and described.

DESCRIPTION

FIG. 1 is a first perspective view of my new oxygen conserving regulator;

FIG. 2 is a second perspective view thereof;

FIG. 3 is a front view thereof;

FIG. 4 is a top view thereof;

FIG. 5 is a left side view thereof;

FIG. 6 is a right side view thereof;

FIG. 7 is a bottom view thereof; and,

FIG. 8 is a rear view thereof.
